(57) **CLAIM**

The ornamental design for a bin, as shown and described.

DESCRIPTION

FIG. 1 is a perspective view of the bin;

FIG. 2 is a front view thereof;

FIG. 3 is a rear view thereof;

FIG. 4 is a left-side view thereof;

FIG. 5 is a right-side view thereof; and,

FIG. 6 is a top view thereof.

The broken lines shown in the drawings are for the purpose of illustrating portions of the bin and form no part of the claimed design.

1 Claim, 6 Drawing Sheets(56)
